UNITED STATES PATENT OFFICE.

ALBERT C. McFARLANE, OF COLORADO SPRINGS, COLORADO.

FLUID-PRESSURE TOOL.

1,010,660.

Specification of Letters Patent.

Patented Dec. 5, 1911.

Application filed April 27, 1910. Serial No. 557 895.

To all whom it may concern:

Be it known that I, ALBERT CHARLES McFARLANE, a citizen of the United States, and a resident of Colorado Springs, in the county of El Paso and State of Colorado, have invented a new and Improved Fluid Pressure Tool, of which the following is a full, clear, and exact description.

The invention relates to rock drills, hammers and like devices, in which compressed air or a like fluid under pressure is used as the motive agent.

The object of the invention is to provide a new and improved fluid pressure tool, arranged for running the tool at a high speed and with economy in the use of the motive agent, to reduce jar and vibration to a minimum, and to prevent breaking of the operating parts, especially when the tool is running without the drill being in place. In order to attain this object, use is made of a valveless piston hammer, reciprocating in a valveless cylinder, the piston hammer in its movement controlling the cut-off and exhaust of the motive agent.

A practical embodiment of the invention is represented in the accompanying drawings, forming a part of this specification, in which similar characters of reference indicate corresponding parts in all the views.

Figure 1 is a side elevation of the improvement, arranged as a rock drill; Fig. 2 is a longitudinal sectional elevation of the same; Fig. 3 is an enlarged longitudinal central section of the same on the line 3—3 of Fig. 7 and showing the hammer head in withdrawn or starting position; Fig. 4 is a similar view of the same on the line 4—4 of Fig. 7 and showing the hammer head in extreme forward position at the time the drill is removed; Fig. 5 is an enlarged central section of the stopping bar and adjacent parts; Fig. 6 is a transverse section of the improvement on the line 6—6 of Fig. 4; Fig. 7 is a like view of the same on the line 7—7 of Fig. 4; Fig. 8 is a similar view of the same on the line 8—8 of Fig. 4; Fig. 9 is a similar view of the same on the line 9—9 of Fig. 4; Fig. 10 is a similar view of the same on the line 10—10 of Fig. 4; Fig. 11 is a like view of the same on the line 11—11 of Fig. 4; Fig. 12 is a similar view of the same on line 12—12 of Fig. 4; and Fig. 13 is a longitudinal central section of a solid piston hammer. The cylinder A of the fluid pressure tool

which the smaller forward bore A² terminates at its forward end in an annular exhaust chamber A³ connected with a tapering opening A⁴ in the forward end of the cylinder A, the said opening A⁴ containing a chuck B holding the drill or other tool C to be operated on by a piston hammer D, reciprocating in the small bore A² and having an enlarged head D' reciprocating in the large bore A' of the cylinder A.

The rear end of the cylinder A is closed by a head E having a flange E' pressed against the rear end of the cylinder A by a shoulder F' formed on a sleeve F, screwed or otherwise secured to the exterior surface of the cylinder A, the said sleeve forming in the rear of the cylinder A an admission chamber F², into which passes the compressed air or other fluid under pressure, supplied through a pipe G having a valve G' under the control of the operator for controlling the fluid pressure passing into the chamber F². In the rear contracted end F³ of the sleeve F is screwed or otherwise secured the cylinder H of a stopping or a feed bar, and in the said cylinder H reciprocates a piston I having its piston rod I' extending through a head H' arranged on the outer end of the cylinder H. The outer end of the piston rod I' carries a point J adapted to engage the material in the mine or other place, so that the fluid pressure entering the admission chamber F² and the forward end of the cylinder H exerts a pressure on the piston I, to force the cylinder A and the parts carried thereby in a forward direction, to feed the drill C into the material to be cut. The cylinder H is locked in place on the reduced end F³ of the sleeve F by a nut H², as indicated in the drawings.

In the cylinder A and extending through the flange E' are arranged a number of longitudinally-extending inlet ports a, preferably four in number, as indicated in Figs. 6, 7 and 8, and the forward ends of the said ports a open into an annular groove b in communication with the large bore A' of the cylinder A near the forward end of the said bore A', as plainly shown in Figs. 2, 3 and 4. Longitudinally-extending charge grooves c are formed in the wall of the large bore A' of the cylinder A, the said grooves c terminating at their forward ends a distance from the annular groove b, as indicated in Figs. 2 and 3, and from the large bore A' of the cylinder A lead exhaust ports d to

the peripheral face of the cylinder A, the said ports also extending through the sleeve F, as shown in Fig. 7. The exhaust ports *d* are located somewhat in the rear of the 5 forward ends of the grooves *c*.

Now when the several parts are in position, as shown in Figs. 2 and 3, and the operator opens the valve G', then the motive agent can pass into the chamber F² and by 10 way of the ports *a* into the annular groove *b*, from which the motive agent can pass rearwardly in the large bore A' and into the forward ends of the grooves *c*, to allow the motive agent to travel farther rearwardly in these grooves *c*, to finally pass into the bore A' at a point between the cylinder head E and the rear end of the hammer head D', to force the piston hammer D forward and to cause the piston hammer D 15 to exert a blow on the drill C mounted to slide in the chuck B. During the forward movement of the hammer D and its head D', the head D' finally reaches the forward ends of the grooves *c*, to cut off the motive 20 agent from the said grooves *c*, and then the piston hammer D travels forward under the pressure contained in the rear end of the bore A' of the cylinder A. During the further forward movement of the piston hammer 25 D, its head D' finally uncovers the exhaust ports *d* so that the motive agent in the large bore A' of the cylinder A passes to the atmosphere, and the piston hammer D is immediately returned to its starting position, as shown in Fig. 3, by the action of 30 the motive agent on the annular shoulder D² formed between the piston hammer D and its head D', and the above described operation is then repeated, that 35 is, the piston hammer is again moved forward by the action of the motive agent passing into the rear end of the large bore A' by way of the ports *a*, the recess *b*, the forward end of the bore A' and the grooves *c*, 40 as previously explained. It is understood that during the forward stroke of the piston hammer D, the motive agent presses on the shoulder D², to cushion the piston hammer and to return the piston hammer to its 45 starting position.

For rock drills it is preferred to provide the piston hammer D and its head D' with a recess D³, opening at its rear end into the bore A', and into which extend the reduced 55 ends E², E³ of the cylinder head E. From the forward end of the recess D³ lead ports *e* into an annular groove *e'* formed on the peripheral face of the piston hammer D, and when the piston hammer D is in the 60 starting position as shown in Fig. 3, then this annular groove *e'* is in register with the forward end of the large bore A' adjacent to the annular groove *b*, and consequently the live motive agent can pass from this annular groove *b* into the annular groove *e'*.

and by way of the ports *a* into the recess D³, to act on the hammer piston D, with a view to assist in propelling the same forward. Thus by the arrangement described a double feed of motive agent is had into the large 70 bore A' of the cylinder A, to insure a quick forward stroke of the hammer piston D, thus allowing of running the machine at a high speed. A double exhaust also takes place in this case, as the annular groove *e'* moves into register with the exhaust chamber A³ at the time the hammer piston D nears the end of its forward stroke, so that the exhaust motive agent can pass through the ports *e* and annular groove *e'* into the 75 exhaust chamber A³, from which the exhaust motive agent can pass to the atmosphere by way of the exhaust ports *f*. The reduced ends E², E³ of the cylinder head E, extending into the recess D³ of the hammer, cut down the clearance space and thus increase the economy by decreasing the gas or air consumption.

As shown in Figs. 2 and 5, the rear end of the drill C extends into the exhaust chamber A³, and in order to prevent damage to the piston hammer D at the time the machine is running and the drill C is removed, the following arrangement is made: On the peripheral face of the piston hammer D are formed longitudinally-extending grooves *g* leading from the shoulder D² to within a short distance of the annular groove *e'*, so that when the drill C is removed and the piston hammer D moves into the extreme 90 forward position shown in Fig. 4, then the motive agent in the forward end of the bore A' can pass by way of the grooves *g* into the exhaust chamber A³, and at the same time live motive agent can pass from the 95 ports *a* by way of ports *h* into the forward end of the large bore A' of the cylinder A, so as to bring the piston hammer D to a stop, as the live motive agent can now exhaust from the rear end of the bore A' by 100 way of the sets of exhaust ports *d*, *e*, *f* to the atmosphere. The rear end of the head D' of the piston D is provided with a deflecting flange D⁴ opposite the ports *h* at the 105 time the hammer piston D is at the extreme 110 forward position and the drill C is removed. The cylinder A is turned by the operator having hold of a handle K attached to the cylinder, and the exhaust motive agent leaving the exhaust ports *d* and *f* is deflected in a rearward direction by collars L and L', having rearwardly extending flanges L², L³, to form annular chambers 115 into which passes the exhaust motive agent from the ports *d* and *f*, to deflect the exhaust motive agent in a rearward direction. The collars L and L' also prevent grit and other material loosened by the drill C from 120 passing by way of the exhaust ports *d* and *f* into the cylinder A, thus insuring long life 125 130

of the working parts. The collar L serves as a lock nut for the forward end of the sleeve F.

When the machine is not in use it is desirable to hold the piston I, the piston rod I' and the point J in a forward position relative to the cylinders H and A, and for this purpose use is made of a pair of spring arms O, secured to the head E at the rear end thereof so that the spring arms O project into the cylinder H, and their enlarged forward ends O' are adapted to engage a socket I² formed in the piston rod I' of the piston I, to hold the said piston I, the piston rod I' and the point J temporarily locked in place.

When the machine is set up in position in a mine or other place and motive agent is passed into the forward end of the cylinder H, as previously explained, then the pressure against the piston I moves the same rearwardly and the socket I² out of engagement with the enlarged ends O' of the spring arms O.

For pneumatic hammers and like tools it is desirable to use but a single admission and a single exhaust, and in this case the piston hammer is made solid, as shown in Fig. 13; the solid piston hammer D⁵, however, taking the place of the hollow or recessed piston hammer D, shown in Figs. 3 and 4, and the cylinder head E being without the reduced ends E², E³.

Having thus described my invention, I claim as new and desire to secure by Letters Patent:

1. A fluid pressure tool comprising a cylinder having concentric bores and longitudinal inlet ports connected at the rear end of the cylinder with a fluid pressure supply, the forward ends of the said inlet ports opening into an annular groove in the wall of the large cylinder bore near the forward end thereof, the said bore wall having lengthwise-extending charging grooves spaced rearwardly from the said annular groove, the said large bore having exhaust ports leading to the atmosphere, and a piston hammer mounted to reciprocate in the small cylinder bore and having an enlarged head fitting the large cylinder bore, the said head uncovering the said exhaust ports near the end of its stroke.

2. A fluid pressure tool comprising a cylinder having concentric bores and longitudinal inlet ports connected at the rear end of the cylinder with a fluid pressure supply, the forward ends of the said inlet ports opening into an annular groove in the wall of the large cylinder bore near the forward end thereof, the said bore wall having lengthwise-extending charging grooves spaced rearwardly from the said annular groove, the said large bore having exhaust ports leading to the atmosphere, a piston

hammer mounted to reciprocate in the small cylinder bore and having an enlarged head fitting the large cylinder bore, the said head uncovering the said exhaust ports near the end of its stroke, the said piston hammer being formed with a recess opening at its rear end into the large cylinder bore, and ports in the piston hammer leading from the forward end of the said recess to connect with the forward end of the said large cylinder bore at the time the hammer piston is in a retracted starting position.

3. A fluid pressure tool, comprising a cylinder having concentric bores and longitudinal inlet ports connected at the rear end of the cylinder with a fluid pressure supply, the forward ends of the said inlet ports opening into an annular groove in the wall of the large cylinder bore near the forward end thereof, the said bore wall having lengthwise-extending charging grooves spaced rearwardly from the said annular groove, the said large bore having exhaust ports leading to the atmosphere, a piston hammer mounted to reciprocate in the small cylinder bore and having an enlarged head fitting the large cylinder bore, the said head uncovering the said exhaust ports near the end of its stroke, the said piston hammer being formed with a recess opening at its rear end into the large cylinder bore, and ports in the piston hammer leading from the forward end of the said recess to connect with the forward end of the said large cylinder bore at the time the hammer piston is in a retracted starting position, the said hammer piston ports being adapted to register with an annular exhaust chamber in front of the small cylinder bore at the time the hammer piston is at the end of its forward stroke.

4. A fluid pressure tool, comprising a cylinder having concentric bores and longitudinal inlet ports connected at the rear end of the cylinder with a fluid pressure supply, the forward ends of the said inlet ports opening into an annular groove in the wall of the large cylinder bore near the forward end thereof, the said bore wall having lengthwise-extending charging grooves spaced rearwardly from the said annular groove, the said large bore having exhaust ports leading to the atmosphere, a piston hammer mounted to reciprocate in the small cylinder bore and having an enlarged head fitting the large cylinder bore, the said head uncovering the said exhaust ports near the end of its stroke, and means for directing the exhaust rearwardly.

5. A fluid pressure tool, comprising a cylinder having concentric bores and longitudinal inlet ports connected at the rear end of the cylinder with a fluid pressure supply, the forward ends of the said inlet ports opening into an annular groove in the wall

of the large cylinder bore near the forward end thereof, the said bore wall having lengthwise-extending charging grooves spaced rearwardly from the said annular groove, the said large bore having exhaust ports leading to the atmosphere, a piston hammer mounted to reciprocate in the small cylinder bore and having an enlarged head fitting the large cylinder bore, the said head uncovering the said exhaust ports near the end of its stroke, the said piston hammer being formed with a recess opening at its rear end into the large cylinder bore, ports in the piston hammer leading from the forward end of the said recess to connect with the forward end of the said large cylinder bore at the time the hammer piston is in a retracted starting position, and a plug for closing the rear end of the large bore of the said cylinder, the plug having forwardly-extending reduced portions adapted to extend into the said piston hammer.

6. A fluid pressure tool, comprising a cylinder having concentric bores and longitudinal inlet ports connected at the rear end of the cylinder with a fluid pressure supply, the forward ends of the said inlet ports opening into an annular groove in the wall of the large cylinder bore near the end thereof, the said bore wall having lengthwise-extending charging grooves spaced rearwardly from the said annular groove, the said large bore having exhaust ports leading to the atmosphere, and auxiliary ports ahead of the said exhaust ports and opening into the said inlet ports, and a piston hammer mounted to reciprocate in the small cylinder bore and having an enlarged head fitting the large cylinder bore, the said head uncovering the said exhaust ports near the end of its stroke.

7. A fluid pressure tool comprising a valveless cylinder having concentric bores,

an admission chamber at the rear end of the cylinder connected with a fluid pressure supply, and inlet ports connected with the admission chamber, the wall of the large cylinder bore having an annular groove into which the said inlet ports open, and charging grooves spaced from the said annular groove, the large cylinder bore having exhaust ports leading to the atmosphere, and a piston hammer mounted to reciprocate in the small cylinder bore and having an enlarged head fitting the large cylinder bore, the said head controlling the cut-off and exhaust of the fluid pressure.

8. A fluid pressure tool comprising a cylinder, a head closing the rear end of the cylinder and having a flange, a sleeve screwed on the cylinder and having a shoulder engaging said flange to press the same against the rear end of the cylinder, the said sleeve forming an admission chamber at the rear of the cylinder, a fluid pressure supply connected with said admission chamber, longitudinally-extending inlet ports in said cylinder and extending through said flange, the said ports opening at their forward ends into an annular groove in communication with the bore of the cylinder, longitudinally extending charging grooves formed in the wall of the cylinder and spaced at their forward ends from the said annular groove, the said cylinder having exhaust ports, and a piston hammer mounted to reciprocate in the said cylinder and controlling the cut-off and exhaust of the fluid pressure.

In testimony whereof I have signed my name to this specification in the presence of two subscribing witnesses.

ALBERT C. McFARLANE.
